UNITED STATES PATENT OFFICE.

PETER C. WIEST, OF YORK, PENNSYLVANIA.

TIRE-REMOVER.

959,669.

Specification of Letters Patent. Patented May 31, 1910.

Application filed May 19, 1909. Serial No. 496,959.

To all whom it may concern:

Be it known that I, PETER C. WIEST, a citizen of the United States of America, residing at York, in the county of York and 5 State of Pennsylvania, have invented certain new and useful Improvements in Tire-Removers, of which the following is a specification.

This invention relates to tools for removing tires from wheels, and more particularly to a tool especially adapted to be used for removing automobile clench tires, the object being to provide a tool which is so constructed that the outer casing can be 15 readily removed without any danger of injuring the inner tube.

A further object of my invention is to provide a tool with a revoluble conical head adapted to be forced under the flange of 20 the casing and the rim, so that by sliding the tool around the periphery of the rim, the flange will be drawn out of the clenched rim.

A still further object of the invention is 25 to provide the head with an annular flange for holding the tool in position on the rim after it has been inserted under the flange of the casing, so that all danger of the same slipping out after once being inserted, is 30 prevented, said flange also serving the purpose of holding the flange of the casing in such a position that as the tool is forced around the periphery of the tire, it will be drawn from under the clenched rim, in such 35 a manner that the casing will not be injured in any way.

Another object of my invention is to provide a tool having a hooked end for starting, or loosening the casing from under the 40 clenched rim, so that the revoluble head can be placed in position.

A still further object is to provide very 45 novel means for mounting the revoluble head upon the handle, so that the same can freely rotate thereon without any danger of its coming off, or injuring the inner tube.

With these objects in view, the invention consists in the novel features of construction, combination and arrangement of parts 50 hereinafter fully described and pointed out in the claims.

In the drawing forming a part of this specification: Figure 1 is a side elevation of a portion of an automobile wheel, showing 55 my improved tool inserted under the outer casing in position to be operated to

remove the casing. Fig. 2 is a vertical section through the wheel, showing the position my improved tool assumes when the casing is being removed. Fig. 3 is an end view 60 of my improved tool, and Fig. 4 is a side elevation partly in section of my improved tool.

In carrying out my improved invention, I employ a cylindrical handle A provided 65 with a flattened end-portion A', having its extreme end bent at an angle, as shown at A² forming means for loosening the outer casing from under the clenched rim of the automobile wheel. The other end of the 70 handle A is reduced as shown at A³, on which is revolubly mounted a sleeve B having a conical head C provided with an annular flange D.

The end of the head C is provided with 75 an annular recess surrounding the reduced portion of the handle, in which is adapted to be arranged a washer E, through which extends an outwardly projecting pin F, formed integral with the end of the reduced 80 portion A³ of the handle, said pin having its end swaged for locking the washer to the same. The washer also locks the revoluble head and sleeve in position on the handle in such a manner that the head is allowed to 85 rotate freely thereon.

In placing my improved tool in position to remove the outer casing of an automobile wheel, the angled end is first forced under the flange of the casing, and by exerting a 90 downward pressure on the handle, the casing is raised so that a block or any other suitable chuck can be placed under the same, and the angled end is then withdrawn, and the revoluble head inserted, and by forcing 95 the handle around the rim, the revoluble head will revolve on the periphery of the rim, in such a manner that the flange of the casing will be drawn outwardly from under the clenched-rim without any danger of the 100 tool slipping inwardly, so as to puncture the inner tube, and it will be seen that as the tool is forced around the rim, the flange of the casing is held on the conical portion, so as to prevent the same from becoming 105 injured.

From the foregoing description it will be seen that I have provided a very novel tool for removing the outer casing of automobile wheels, which is so constructed that the 110 same can be moved freely around the periphery of the rim after the same has been

inserted under the flange of the casing. It will be seen that as the tool is forced around the rim, the head will revolve upon the handle, so as to allow the same to roll over the rim, whereby the friction is decreased, which enables the operator to move the tool easily.

Having thus fully described my invention, what I claim as new and desire to set 10 cure by Letters Patent is:

1. A pneumatic tire remover embodying a handle having a reduced end portion, a sleeve of uniform diameter fitting loosely around the reduced portion of the handle, 15 and a conical member or head mounted to turn freely on the reduced portion of the handle independently of the sleeve and beyond the outer extremity of the sleeve, said

head being provided with a circumferential flange at its outer end where it is of the 20 greatest diameter.

2. A pneumatic tire remover embodying a handle, a sleeve mounted to turn freely thereon, and a conical head also mounted to turn freely thereon independently of and 25 reversely to said sleeve, said head being provided with a circumferential retainer flange at its outer end where it is of the greatest diameter.

In testimony whereof I have hereunto set 30 my hand in presence of two subscribing witnesses.

PETER C. Wiest.
